DECORATIVE LIGHT FIXTURE

Dean Myers, Newport Beach, Calif., assignor to Poly-
Optics, Inc., a corporation of California

Filed Jan. 22, 1969, Ser. No. 15,443

Term of patent 14 years

Int. Cl. D26—02

U.S. Cl. D48—20

The fixture is a perspective view of a decorative light fixture showing my new design, the opposite side having substantially the same appearance.

I claim:

The ornamental design for a decorative light fixture, substantially as shown and described.
